UNITED STATES PATENT OFFICE.

JAMES C. LEDBETTER, OF BROOKLYN, NEW YORK, ASSIGNOR, BY MESNE ASSIGNMENTS, TO LIBERTY NATIONAL BANK, TRUSTEE, OF SYRACUSE, NEW YORK.

GARMENT PRESS.

REISSUED

Application filed October 27, 1923. Serial No. 671,121.

To all whom it may concern:

Be it known that I, JAMES C. LEDBETTER, a citizen of the United States, residing at Brooklyn, in the county of Kings and State of New York, have invented certain new and useful Improvements in Garment Presses, of which the following is a specification.

This invention relates to pressing machines, and particularly to power pressing machines for garment pressing and laundry pressing work.

An object of the invention is to produce an improved garment pressing machine having high power pressing mechanism enabling a garment to be thoroughly treated and pressed with great pressure without effort on the operator's part. A further object is to produce an improved combination pressing machine possessing both manual and power pressing mechanism, being a machine which is manually closed by the operator and which automatically turns on its power to produce final pressure without effort on the part of the operator, and which machine subsequently opens by power, thereby rendering unnecessary the use of counterweights or springs to lift the press head. A further object is to provide an improved press adjustment means whereby the relative position of the press members is conveniently placed under the control of the operator.

The accompanying drawing illustrates an embodiment of the invention serving to illustrate the construction and principle thereof as well as the mode of operation, all of which may be varied or modified without necessarily departing from the scope of the invention.

Figure 1 illustrates the pressing machine in side elevation with the power operating mechanism thereof shown in section.

Figure 2 shows a sectional view on the line 2—2.

Figure 3 shows a detailed sectional view of a motor employed to open the press by power.

Referring now more particularly to the drawing for a detailed description of the invention, there is shown a pressing machine frame 4 of any suitable design and upon which may be mounted a press buck 5. A press head 6 is carried on the forward end of a press lever 7 which is pivoted at 8 on

the frame 4; and it is observed how the head 6 and buck 5 provides co-operating press members which open and close in movable relation for the purpose of pressing garments. Suitable steam-heating and steam-spraying means may be provided for either 60 or both said press members 5 and 6 for treating the garments. A hand-hold piece, or handle 9, is provided by which the operator manually closes the head 6 down upon the buck 5. The press lever 7 may be provided 65 on the rear end thereof with a counter-weight 10 which balances the press head 6 thereby preferably causing the press lever 7 to stand poised at any particular place, which enables the operator to quickly close 70 the head 6 down upon the buck 5. This particular construction and mode of operation constituting a part of my invention enables a pressing machine of this character to be produced without necessarily employing springs or over-balancing weights to lift the head 6 after the press operation is completed, and thus I have described the preferred construction as being so arranged that the counter-weight 10 and head 6 substantially balances one with the other.

A main operating toggle constituting pivotally joined links 12 and 13 is pivoted at its upper end at 14 to the press lever 7 and at its lower end upon a cam 15 supported in 85 the frame. The cam is fixed to a shaft 16, roller bearing 17 being interposed between cam 15 and hub 18 made a part of the lower toggle link 13. A power arm 19 is integral with the toggle link 13 and projects forwardly from the hub 18; and the toggle link 13 and arm 19 constitutes a power operated bell crank swingable on the cam as a pivot.

The shaft 16 has a worm wheel 20 fixed thereto and a worm pinion 21 engages the wheel 20. A reach rod 22 provided with a hand wheel 23 is fixed to the worm 21, thereby enabling the operator standing at the front of the machine to rotate the worm 21, which shifts the cam eccentric element 15 up 95 and down to vary or regulate the height of the toggle 12 and 13; and this movement adjustably varies the relative position of the pressing members 5 and 6 thereby rendering the machine most efficient in operation for 100 the various kinds and thicknesses of garment pressing work. By turning the hand wheel 23, the cam 15 may be elevated or rotated in

either direction to bring the cam up to its higher or lower position to adapt the press to thinner or thicker garments.

A power cylinder 25 is arranged over the forward end of the power arm 19 and may be anchored to the frame 4; and the cylinder carries a freely floating unattached piston 26. A substantially soft coil compression spring 27 is interposed between the piston and lower end of the cylinder and functions to return the piston 26 to its upper-most normal position. A push rod 29 is pivoted at 30 to the power arm and has a contact head 31 which is engaged by the piston 26 when the machine is operating under power. The piston 26 is usually held in a position slightly above the push rod head, for in designing this pressing machine improvement I have so constructed it that the manual operation involved in closing the head 6 down upon the buck is carried out without moving the pistons in the one or more cylinders employed, the object thereof being to reduce friction of moving parts, thereby rendering the pressing machine more easily closed. The lower end of the cylinder 25 is provided with an open head which permits the push rod 29 to freely move up and down in the cylinder when the operator manually closes the head by pulling downwardly on the handle 9.

A power press opening cylinder or motor 33 is connected with a pipe 34 to the upper end of the cylinder 25 whereby the steam employed to operate the cylinder 25 may be discharged or exhausted therefrom to the cylinder 33 for breaking the toggle and raising the head by force of the exhaust from the cylinder 25. The press head lifting motor 33 is fitted with a piston 35 which carries a valve stem 36 as an integral part thereof. The stem 36 works back and forth through a cylinder head 37 during the movement of the piston 35 in the cylinder 33. A soft coil spring 38 is confined between the piston 35 and cylinder head 37 for the purpose of returning the piston 35 to its normal position near the forward end of the cylinder 33 to save the operator moving the piston during the manual closing stroke; and after the press head has been lifted to its uppermost position by the action of the piston 35, the spring 38 returns it to the other end of the cylinder 33. The motor 33 is fitted with a connecting rod in the nature of a push rod 39 and pivotal connecting link 45 which has one end pivotally connected at 40 to the toggle 12-13 and the other end 44 rests in engagement with the outer end of the piston stem 36 of the piston 35 thereby closing and sealing a piston exhaust passage 41 without loss of steam pressure when the piston is pushing against the push rod 39 to lift the head 6. However, after the pis-

ton passes beyond certain provided auxiliary exhaust ports 42 in the cylinder, the pressure of steam acting on the piston is dissipated sufficiently to permit the spring 38 to react forwardly on the piston thereby moving the valve stem 36 away from the ball headed end 44 of the push rod 39 which uncovers the exhaust passage 41 and permits the piston to quickly return to the forward or right hand end of the cylinder 33; and so when it comes time to close the press, the piston 35 has already passed out of the way of all manually operating parts thus saving the operator's efforts, and permitting the push rod 39 to travel through the cylinder head 37 and approach the front end of the cylinder 33 where the ball valve headed rod 39 takes up a position over the end of the valve stem 36 closing the exhaust passage 41 to again make ready for another power opening operation.

A cushion spring 43 is provided at the forward end of the cylinder against which the piston 35 comes to rest in a manner designed to closely fit the push rod head 44 over the piston valve exhaust passage 41 when the pressing machine closes, and thus seal the exhaust 41 so that steam or air under pressure entering the motor 33 will positively act. The push rod head 44 performs the double function of sealing the passage 41 and taking the thrust of the piston 35, and it moves freely through a central opening made in the cylinder head 37. It is to be appreciated that this pressing machine is manually closed by the operator only, and no pressing is actually done by him, for by the time the push rod 39 and piston 35 reach the spring cushion 43, the power cylinder 25 will have been automatically turned on to perform the real work of pressing as will be described.

A steam or air pressure supply main 46 not only supplies steam to the pressing members 5 and 6 but conveys steam to the cylinder 25 as well; and a valve 47 cuts off and turns on the steam to operate the cylinder. The operation of the valve 47 is automatically accomplished through the agency of a control rod 48 pivotally connected at its lower end to the power arm 19. The upper end of the rod 48 connects through a pull spring 49 with a valve handle 50 designed to operate the valve 47 with a quick snap closed and snap opened action when the power arm is manually worked up and down respectively. A power control opening pedal 52 is pivoted on the frame and connects with an exhaust valve 53 included in the exhaust pipe 34, and this pedal controls the press opening action. A spring 54 is placed to hold the valve 53 normally closed and the pedal 52 up. A link 51 or other suitable means connects the pedal 52 and exhaust valve 53.

- In operation the head is closed by hand motor means to the closed press, and power means for raising one press member high above the other from closed pressing position to fully opened position.
- 5 sufficient tension to quickly open the valve 47 which permits steam to flow to the cylinder and drive the piston 26 down to overtake the push rod 29 which action automatically completes the operation of straightening the 70
10 toggle 12-13 to produce extreme head and buck pressure. At the same time this movement of parts occur, the other push rod 39 takes up a position in contact with the valve stem 36 as hereinbefore described and as 75
15 shown in position in Figure 3. Having pressed, steamed, and dried the garment on the buck, the operator now depresses the pedal 52 which discharges steam or the other pressure from the cylinder 25 into the cylinder 33 quickly opening the press by the power of the exhaust from the power cylinder and lifting the head without 80
20 springs or weights or manual effort.
- In order to avoid undue slamming of 25 parts or too quickly opening the press, the power cylinder is provided with an air cushion dashpot in effect already described. The dashpot consists of the cylinder head 37 together with the piston 35 and valve 30 stem 36 which produces an air lock between the parts 37 and 35 when the piston valve stem 36 moves into sliding fit with the head 37 thus confining air thereinbetween under pressure which increases rapidly until the 85
35 movement of parts is stopped against the air cushion. At this time the ports 42 are uncovered to vent both cylinders 25 and 33 which permits both pistons to move away from the push rods to the upper and front 90
40 ends of the cylinders freeing the press of any piston or cylinder connections and thus setting the machine for the next operation. A dashpot regulating valve 55 is placed in the dashpot end of the motor 33 for the purpose of regulating the escape of compressed air to quietly bring the head, press lever, and other parts to rest in open and up position.
- It is desirable to make power presses operate manually as far as closing the press is concerned for if the closing stroke is executed by power, there is danger of an accident for the operator may by chance get his 95
50 hands between the jaws or head and buck of the press. This danger is always avoided when the operator is compelled to bring his hands up to the handle 9 to close the press. The closing operation is very easily accomplished for the press lever is balanced, and there exists no friction of moving parts.
- 55 What I claim is:—
1. A pressing machine comprising in combination, cooperating press members, means to close the press manually, means to produce final pressure by the application of 100
60 power means to the closed press, power means for raising one press member high above the other from closed pressing position to fully opened position, a press lever operated by one end of the bell crank, cooperating press members operable to open and close by the action of 105
65
2. A pressing machine comprising in combination, cooperating press members, means to close the press manually, means to produce final pressure by the application of motor means to the closed press, power means for raising one press member high above the other from closed pressing position to fully opened position, and a dashpot cushion to retard the opening movement of the press member. 70
75
3. A pressing machine comprising in combination, cooperating press members, means to close the press manually, means to produce final pressure by the application of motor means to the closed press, power means for raising one press member high above the other from closed pressing position to fully opened position, and a dashpot cushion made an integral part of the power press opening means. 80
85
4. A pressing machine comprising in combination, cooperating press members, means to close the press manually, means to produce final pressure by the application of motor means to the closed press, power means for raising one press member high above the other from closed pressing position to fully opened position, and a hand wheel regulating device for varying the cooperative relative pressing position of the 90
95
100 press members.
5. A pressing machine comprising in combination, cooperating press members, means to close the press manually, means to produce final pressure by the application of motor means to the closed press, power means for raising one press member high above the other from closed pressing position to fully opened position, a toggle connected with the said one press member being raised, a cam pivot bearing supporting the toggle, and a hand regulating device to adjustably rotate the cam. 105
110
6. A pressing machine comprising in combination, cooperating press members, means to close the press manually, means to produce final pressure by the application of motor means to the closed press, power means for raising one press member high above the other from closed pressing position to fully opened position, a press lever carrying one of the members, said manually closing means constituting a handle carried on one of the press members, and a counterbalance weight carried on the press lever to balance the operable press member. 115
120
125
7. A pressing machine comprising in combination, a frame, a bell crank pivoted therein, a press lever operated by one end of the bell crank, cooperating press members operable to open and close by the action of 130
- 85

- the press lever, a power cylinder connected to the other end of the bell crank to close the press members, and motor means driven by the exhaust of the power cylinder to rock 5 the bell crank to open the press.
8. A pressing machine comprising in combination, a frame, a bell crank pivoted therein, a press lever operated by one end of the bell crank, cooperating press members operable to open and close by the action of the press lever, a power cylinder connected to the other end of the bell crank to operate the press members, motor means driven by the exhaust of the power cylinder to rock 10 15 the bell crank to open the press, an adjustable pivot supporting the bell crank, and means operable from the front of the machine for adjusting the pivot to vary the closing pressure of the press members.
- 16 20 9. A pressing machine comprising in combination, a frame, a press lever pivoted therein, cooperating press members operable by the lever to open and close the press, a toggle connected to the press member, a power arm fixed to the toggle, manually closing press means, a power pressure motor connected to the power arm, means to automatically turn on the power motor at the end of the manual closing operation, a motor arranged to open the press by power, a manually operable means designed to control the motor, and means to automatically cut off the power motor when the press opening motor begins to act.
- 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950
- the press lever, a power cylinder connected to the other end of the bell crank to close the press members, fluid supply means running to one cylinder to produce extreme pressure, an exhaust connection extending from the cylinder producing extreme pressure to the other cylinder which acts to open the press by power, manual press closing means which governs the fluid supply means, and manual control means controlling the operation of the exhaust connection.
13. A garment press comprising in combination cooperating press members, a power cylinder, a piston freely floating therein, a push rod engaging the piston and connecting with the members to produce pressure, and means acting on the piston to return it to normal inactive position after producing final pressure.
14. A garment press comprising in combination cooperating press members, a power cylinder, a piston freely floating therein, a push rod engaging the piston and connecting with the members to produce pressure, means acting on the piston to return it to normal inactive position after producing final pressure, and another cylinder connected with the press members adapted to open the press.
15. A garment press comprising in combination cooperating press members, a power cylinder, a piston freely floating therein, a push rod engaging the piston and connecting with the members to produce pressure, means acting on the piston to return it to normal inactive position after producing final pressure, another cylinder connected with the press members adapted to open the press, and a connection existing between the two cylinders enabling the exhaust of one cylinder to operate the other cylinder.
16. A garment press comprising in combination cooperating press members, a power cylinder, a piston freely floating therein, a push rod engaging the piston and connecting with the members to produce pressure, means acting on the piston to return it to normal inactive position after producing final pressure, another cylinder connected with the press members adapted to open the press, a connection existing between the two cylinders enabling the exhaust of one cylinder to operate the other cylinder, and manual control means adapted to open and close the said connection.
17. A garment pressing machine comprising in combination, pressing members designed to open and close one against the other, a hand operated means designed for safely closing the press, a power cylinder, a piston freely floating therein, a push connecting rod extending from the piston to one pressing member adapted to produce high pressure, a lost motion connection provided between the piston and pressing members.
18. A pressing machine comprising in combination, cooperative opening and closing press members, power cylinders connected with the press members, fluid supply means running to one cylinder to produce extreme pressure, an exhaust connection extending from the cylinder producing extreme pressure to the other cylinder which acts to open the press by power, and manual press closing means.
19. A pressing machine comprising in combination, cooperative opening and closing

whereby the piston pushes through the cylinder to produce high pressure and then returns to normal inactive position.

18. A garment pressing machine comprising in combination, pressing members designed to open and close one against the other, a hand operated means designed for safely closing the press, a power cylinder, a piston freely floating therein, a push connecting rod extending from the piston to one pressing member adapted to produce high pressure, a lost motion connection provided between the piston and pressing members whereby the piston pushes through the cylinder to produce high pressure and then returns to normal inactive position, and a power press opening means operable from the cylinder.

19. A garment pressing machine comprising in combination, pressing members designed to open and close one against the other, a hand operated means designed for safely closing the press, a power cylinder, a piston freely floating therein, a push connecting rod extending from the piston to one pressing member adapted to produce high pressure, a lost motion connection provided between the piston and pressing members whereby the piston pushes through the cylinder to produce high pressure and then returns to normal inactive position, a power press opening means operable from the cylinder and comprising a cylinder and piston motor, a venting valve in the press opening means, and means causing the piston to return to normal position after the venting means has acted.

20. A garment pressing machine comprising in combination, pressing members designed to open and close one against the other, a hand operated means adapted to safely close the press, motor means adapted to act on the closed press to produce final pressure, a power press opening means connected with the pressing members, and a dashpot adapted to bring the moving parts quietly to rest.

21. A garment pressing machine comprising in combination, pressing members designed to open and close one against the other, a hand operated means adapted for safely closing the press, motor means adapted to act on the closed press to produce

final pressure, a power press opening means connected with the members, a dashpot adapted to bring the moving parts quietly to rest, and means related with the press opening means to return said means to normal position immediately after the press has opened.

22. A pressing machine comprising in combination co-operating pressing members, a toggle having one end thereof pivotally attached to one of the pressing members, an adjustable pivot supporting the other end of the toggle, means reaching from the adjustable pivot upwardly to a position convenient to an operator whereby the height of the toggle may be regulated to vary the pressure between the pressing members, and means for operating the toggle.

23. A pressing machine comprising in combination co-operating pressing members, a toggle having one end thereof pivotally attached to one of the pressing members, an adjustable pivot supporting the other end of the toggle, means reaching from the adjustable pivot upwardly to a position convenient to an operator whereby the height of the toggle may be regulated to vary the pressure between the pressing members, and manual means for closing the press and operating the toggle.

24. A pressing machine comprising in combination, co-operating pressing members, a toggle employed to open and close the press, a cam pivot related with the toggle, means connected with the cam pivot for rotating the cam to alter the position of the toggle to vary the pressure between the pressing members, a reach rod extending from the means to the front of the pressing machine, means on the end of the reach rod for rotating said rod, and toggle operating means.

25. A pressing machine comprising in combination, a frame, cooperating pressing members carried thereby, a cam pivot rotatably carried on the frame, a press closing mechanism supported on the cam pivot and connected with a pressing member, a worm wheel and pinion connected with the cam, and a reach rod extending from the worm and pinion to the operator's position.

In testimony whereof I affix my signature.
JAMES C. LEDBETTER.
